United States Patent Office.

JOHN R. WIDGEON AND FRED. E. FREY, OF BUCYRUS, OHIO.

Letters Patent No. 83,013, dated October 13, 1868; antedated September 26, 1868.

IMPROVEMENT IN AUTOMATIC BOILER-FEEDERS.

The Schedule referred to in these Letters Patent and making part of the same.

To all whom it may concern:

Be it known that we, JOHN R. WIDGEON and FRED. E. FREY, of Bucyrus, Crawford county, Ohio, have invented a new and improved Construction of Automatic Boiler-Feeders; and we do hereby declare that the following is a full, clear, and exact description thereof, which will enable others skilled in the art to make and use the same, reference being had to the accompanying drawings, forming part of this specification.

Figure 1 represents a vertical section of this invention, taken in the plane indicated by the line xx , fig. 2.

Figure 2 is a plane or top view of the same.

Figure 3 is a front elevation of the driving-gear detached.

Figure 4 is a face view of the seat detached.

Figure 5 is an inside elevation of the revolving chamber.

Figure 6 is a perspective view of the inside and partially of the outside of a case which encloses the automatic boiler-feeder, indicated by figs. 1, 2, 3, 4, and 5, and which is described in Letters Patent issued to said JOHN R. WIDGEON and FRED. E. FREY, March 13, A. D. 1866, and the specifications thereto attached.

Figure 7 is a small steam-pipe, p' , leading from pipe h , fig. 1, into the interior of the casing Q , fig. 6.

This present improvement consists in the construction of boiler-feeders of that class in which a revolving chamber is used steam-tight.

A represents a chamber, made of metal or any other suitable material, and provided with a solid bottom, a , and top b , and also with a toothed rim, c . This chamber revolves on a centre-pin, d , and its bottom, a , works steam-tight against the seat B , which is composed of a thick flat plate, perforated with four holes, $d e f g$, as seen in fig. 4. The opening, e , communicates, through the pipe h , with the steam-space, and the opening, g , through a pipe, i , with the water-space of a steam-boiler. From the hole d leads a pipe, j , to the open atmosphere, and another pipe, k , leading from the hole f to the water-tank, serves to introduce the required supply of water into the chamber A . Said chamber is provided with the ports $l m$, one diametrically opposite the other, and as said chamber revolves, these parts alternately coincide with the holes d and f , and then with the holes e and g and the seat.

The revolving motion of the chamber A is produced by a cog-wheel which gears in the toothed rim c of said chamber. Said cog-wheel is mounted on a shaft, o , which has its bearing in a standard, p , rising from the plate which forms the seat B . When the ports $l m$ are opposite the holes $e g$, the upper part of the chamber fills with steam, and a portion of the water in the chamber runs down in the boiler, and this operation continues until the water in the boiler rises

to the same level with that in the chamber A . When the ports $l m$ are opposite the holes $d f$, the steam contained in the chamber exhausts through the pipe j , and a fresh supply passes into the chamber through the pipe k . This operation continues as long as the boiler is in operation, and the motion of the chamber is not interrupted.

To keep the bottom, a , of the revolving chamber A close and steam-tight against the seat B , and prevent the weight of steam from pressing said bottom of the chamber from said seat, and thus permitting the escape of steam, we have provided the case Q , which sets over said revolving chamber A , and is screwed fast to the seat B by screw-bolts $q q q q$, permitting the centre-pin d to pass through a packing-box at the outer end of said case Q . p' is a small steam-pipe leading from pipe h into the interior of case Q , whereby to introduce steam into said case, which, by its pressure against the top of the revolving chamber A , counteracts the pressure of the steam at the bottom of said revolving chamber; and whilst the steam introduced by the pipe h through the opening e , has a great tendency to part the bottom of said revolving chamber A from close contact with said seat B , and permit the escape of steam between the two faces aforesaid, our device of the case Q , and filling the same with steam by means of the pipe p' , has an equal tendency to keep said two faces together, and prevent the escape of steam.

O is a cock by which steam, and water of condensed steam, may be drawn out of said case when desired.

r is a set-screw by which the pressure of the bottom of said revolving chamber A against said seat B may be slackened should there be too heavy a pressure.

S is a spiral spring coiled around the centre-pin d , and pressed between the top of said revolving chamber A and the interior end of said case Q , serving to keep the bottom of said revolving chamber against said seat when no steam is in said case; otherwise said two faces might part and permit the steam from pipe p' , on its introduction into said case Q , to press against the bottom as well as the top of said revolving chamber A , and prevent its operation.

What we claim as our invention, and desire to secure by Letters Patent, is—

The combination of the case Q with the chamber A , having ports $l m$, and with the seat B provided with holes $d e f g$, substantially as herein described.
